[57] CLAIM

The ornamental design for a chest of drawers, as shown and described.

DESCRIPTION

FIG. 1 is a front elevational view of a chest of drawers showing my new design;

FIG. 2 is a left side elevational view with the drawers partially extended;

FIG. 3 is a right side elevational view of FIG. 1;

FIG. 4 is a top plan view thereof;

FIG. 5 is a bottom plan view thereof;

FIG. 6 is a rear elevational view thereof;

FIG. 7 is an enlarged sectional view taken along line 7—7 of FIG. 1;

FIG. 8 is a front elevational view of a second embodiment of the chest shown in FIG. 1; and,

FIG. 9 is a front elevational view of a third embodiment of the chest shown in FIG. 1.

The top, rear, and sides of the chests of FIGS. 8 and 9 are the same as those shown in views herein, except for height.
